UNITED STATES PATENT OFFICE

148,834

DESIGN FOR A DENTAL CUSPIDOR UNIT

Edwin J. Wester, Rochester, N. Y., assignor to
Ritter Company, Inc., Rochester, N. Y., a corporation of Delaware

Application March 28, 1947, Serial No. 138,011

Term of patent 14 years

(Cl. D24—1)

To all whom it may concern:

Be it known that I, Edwin J. Wester, a citizen of the United States, residing at Rochester, in the county of Monroe and State of New York, have invented a new, original, and ornamental Design for a Dental Cuspidor Unit, of which the following is a specification, reference being had to the accompanying drawings, forming part thereof.

Fig. 1 is a front elevation of a dental cuspidor unit showing my new design;

Fig. 2 is a side elevation;

Fig. 3 is a rear elevation, and

Fig. 4 is a top plan view thereof.

I claim:

The ornamental design for a dental cuspidor unit, substantially as shown.

EDWIN J. WESTER.
